UNITED STATES PATENT OFFICE.

HARLEY J. EARL, OF LOS ANGELES, CALIFORNIA.

DESIGN FOR AN AUTOMOBILE-BODY MOLDING.

58,664.

Specification for Design.

Patented Aug. 9, 1921.

Application filed September 3, 1920. Serial No. 408,029. Term of patent 3½ years.

To all whom it may concern:

Be it known that I, HARLEY J. EARL, a citizen of the United States, residing at Los Angeles, in the county of Los Angeles and State of California, have invented a new, original, and ornamental Design for Automobile-Body Moldings, of which the following is a specification, reference being had to the accompanying drawings, forming a part thereof.

Figure 1 is a side elevation of an automo-

bile body showing my new design of molding for the same.

Fig. 2 is a detail side elevation of a fragment of the molding.

No claim is made for the automobile body as shown.

I claim:

The ornamental design for an automobile body molding as shown.

HARLEY J. EARL.
